UNITED STATES PATENT OFFICE.

CHARLEY C. ROSS, OF SPRINGFIELD, MISSOURI, ASSIGNOR OF ONE-HALF TO J. C. DYSART, OF SPRINGFIELD, MISSOURI.

GATE-LATCH.

1,279,163.

Specification of Letters Patent. Patented Sept. 17, 1918.

Application filed October 26, 1917. Serial No. 198,667.

To all whom it may concern:

Be it known that I, CHARLEY C. ROSS, a citizen of the United States, residing at Springfield, in the county of Greene and State of Missouri, have invented a new and useful Gate-Latch, of which the following is a specification.

The device forming the subject matter of this application is a latching mechanism for a gate, and the invention aims to improve the mounting of the keeper wherewith the latch engages, and to provide novel means whereby the keeper is held in adjusted positions, to coöperate with the latch.

It is within the province of the disclosure to improve generally and to enhance the utility of devices of that type to which the present invention appertains.

With the foregoing and other objects in view which will appear as the description proceeds the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings:—

Figure 1 shows in side elevation, a portion of a support and a portion of a gate, wherewith the structure forming the subject matter of this application has been assembled;

Fig. 2 is a section taken on the line 2—2 of Fig. 1;

Fig. 3 is a section taken on the line 3—3 of Fig. 2; and

Fig. 4 is a fragmental stop plan, showing a lock in place, for holding the gate in a closed position.

The numeral 1 denotes a support of any kind, in the present instance delineated in the form of a tubular post. A U-shaped upper hanger 2 straddles the support 1 and through the rear ends of the arms of the hanger 2, a clamp bolt 3 is passed, to hold the hanger in place on the support 1. The hanger 2 includes a forwardly presented bearing 4. The support 1 is straddled by a lower U-shaped hanger 5 constructed, generally, like the hanger 2. A clamp bolt 6 passes through the arms of the hanger 5 and binds the same on the support 1. The hanger 5 includes a bearing 7. The bearing 7 is provided at its top and at its outer edge

with a seat or notch 8, and in the sides of the bearing 7, at the top thereof, are formed seats or notches 9. To the rear of the seats 9, the hanger 5 is provided with downwardly and laterally inclined surfaces 10 extended to the seats 9.

The numeral 11 designates generally, a keeper, including a side bar 12, the keeper being of U-shape. The side bar 12 is beveled longitudinally, as shown at 14, to form edges 15, the keeper including a bottom bar 17, a top bar 18, and spindles 19 carried by the bars 17 and 18, the spindles 19 being journaled in the bearings 4 and 7 of the respective hangers, the bottom bar 17 coacting with the lower bearing 7, to support the keeper in a vertical position.

The numeral 20 denotes the stile of a gate. The shank 21 of a latch is threaded as shown at 22 into the stile 20, the shank of the latch being provided with a transverse head 26 having arms 27 which extend toward the shank 21, the outer surfaces of the head 26, at its ends, and the outer surfaces of the arms 27 being mutually inclined, as shown at 30, to define upright edges 31. The arms 27 of the head 26 form seats 29 wherein side bar 11 of the keeper is received, when the gate is in latched position. As shown at 28, shank 21 of the latch is provided with inclined surfaces which converge toward the head 26.

In practical operation, the bottom bar 17 of the keeper 11 may be received in the outer seat 8, or it may be received in one of the side seats 9. In this connection, it is to be observed that, should the keeper 11 be swung around too far toward the post 1, the inclined surfaces 10 of the hanger 5 will return the lower bar 17 of the keeper to one of the side seats 9.

The operation of a latch of this general kind is understood by those skilled in the art, but it may be stated that, when the keeper 11 is disposed in an offstanding position with respect to the post 1, and when the bottom bar 17 is engaged in the outer seat 8, the side bar 12 of the keeper 11 is engaged by the shank 21 of the latch, when the gate 20 is swung to a closed position, the side bar 12 engaging with the seat 29, when the spindles 19 rotate in the bearings 4 and 7. Under such circumstances, the keeper 11 swings around until the bottom bar 17 is engaged with one of the side seats 9.

It may happen, however, that, when the gate 20 is swung to a closed position, the bottom bar 17 may be engaged in one of the seats 9, the keeper 11, under such circumstances, standing at right angles to the plane defined by the gate 20 when the latter is in closed position. With the ordinary construction, a latching operation is not always brought about when the parts are arranged as last above described, because one side of the head 26 may strike the outer edge of the side bar 12 of the keeper 11 and bound backwardly, causing the gate to remain in an open position. Owing to the construction employed in the present device, however, such an operation cannot take place, because, when the gate swings to a closed position, the edge 31 of the latch will engage with one of the inclined surfaces 14 of the bar 12, and the edge 15 of the bar 12 will co-operate with one of the inclined surfaces 30 of the latch, thereby insuring a swinging of the keeper 11 and an interlocking engagement between the latch and the keeper.

In Fig. 4 of the drawings, the numeral 35 indicates a pad lock comprising a shackle 36. If desired, the shackle 36 may be made to surround the head 26 of the latch, thereby to form a closure for the space between the end of the arm 27 and the shank 21, so as to hold the bar 12 of the keeper 11 in the seat 29.

Attention is directed to my co-pending application for Letters Patent on a swivel gate latch, Serial No. 198,666, filed on October 26, 1917. The latch mechanism shown in the co-pending application above mentioned, and the latch mechanism shown in this application, have some points in common, namely, the relatively inclined surfaces 30 of the head 26 of the latch, the edge 31 of the latch, the inclined, converging sur-

faces 28 of the shank 31 of the latch, the beveled edges 14 of the keeper 11, and the edge 15 thereof. These features, common to both applications, will be claimed in the co-pending application above alluded to, the claim in this present case being confined to the structural features which are peculiar thereto. A line of division between the two cases thus will be maintained.

Since the shank 21 of the latch is threaded as shown at 22 into the gate stile 20, it will be obvious that the shank 21 may be adjusted endwise, thereby to position the head 26 properly with respect to the bar 12 of the keeper 11.

Having thus described the invention, what is claimed is:—

In a device of the class described, a support; a hanger carried by the support and including a bearing; a loop-shaped keeper comprising a transverse bar supported on the bearing, a spindle journaled in the bearing and a side bar, the bearing having a seat in its outer edge and being provided with side seats, any of the seats being adapted to receive the transverse bar of the keeper, the hanger having downwardly and laterally inclined surfaces leading to the side seats; a gate; and a latch including a shank mounted on the gate, and a transverse head having arms which project toward the shank, the side bar of the keeper being engageable with the shank of the latch to cause the side bar to engage behind either arm.

In testimony that I claim the foregoing as my own, I have hereto affixed my signature in the presence of two witnesses.

CHARLEY C. ROSS.
